have no brown striping, or at the very most, an occasional single short brown pencil stripe, located in the central area thereof. Inside petals — about two-thirds of the inside portion of the body 13-B with the upper most portion 158-C and reverse side outer portion 158-C and the inner portion 12-C, the year around. Inside petals have numerous short dark brown pencil stripes which extend longitudinally from petal base to tip.

Peduncle:

Length.—About 2 cm.

Color.—Light green.

Character.—Strong and upright.

Discoloration after full bloom: The flower becomes 15 lighter to 158-D.

Effect of weather: None.

Persistence: The flowers hang on and dry.

Fragrance: None.

Lasting quality:

On plant.—About 20 days.

As cut flower.—About 14 days.

THE REPRODUCTIVE ORGANS

Stamens:

Number.—Six.

Arrangement.—One opposite each petal.

Anthers.—Size: About 10 mm. Color: Green/Yellow.

Filaments.—Length: About 45 mm. Color: Salmon.

Pollen.—Color: Yellow.

Pistils:

Number.—One.

Style:

Length.—About 35 mm.

Color.—Salmon.

Stigma:

Color.—Salmon.

This plant most nearly resembles its parent, Stalbel, but is distinguished therefrom particularly by the flower color.

I claim:

1. The new and distinctive Alstroemeria cultivar, 20 substantially as herein shown and described, characterized by its almost white wide outer petals and distinguished by the lemon yellow coloring of the inner two-thirds of the inner petal length and the dark pencil stripes which extend from end to end of the inner petal body.
